UNITED STATES PATENT OFFICE.

HAROLD E. NOCK, OF NEWBURYPORT, MASSACHUSETTS, ASSIGNOR TO TOWLE MANUFACTURING COMPANY, OF NEWBURYPORT, MASSACHUSETTS, A CORPORATION OF MASSACHUSETTS.

DESIGN FOR A BONBON DISH OR ANALOGOUS ARTICLE.

Application filed October 20, 1921. Serial No. 509,180. Term of patent 3½ years.

To all whom it may concern:

Be it known that I, HAROLD E. NOCK, a citizen of the United States, residing at Newburyport, in the county of Essex and State of Massachusetts, have invented a new, original, and ornamental Design for a Bon-bon Dish or Analogous Article, of which the following is a specification, reference being had to the accompanying drawing, forming a part thereof.

In the drawing Figure 1 is a plan view

of a bon-bon dish showing my new design; Fig. 2 is a view in elevation; Figs. 3 and 4 are sections on the lines 3—3 and 4—4, respectively, of Fig. 1; and Fig. 5 is a section on the line 5—5 of Fig. 1. In Fig. 1 of the drawing a section only of the border ornamentation is shown.

I claim:

The ornamental design for a bonbon dish or analogous article, substantially as shown.

HAROLD E. NOCK.
